DESIGN FOR WALL-PAPER.

Design No. 12,507, dated October 4, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,507, dated October 4, 1881.

Application filed August 25, 1881. Term of patent 3½ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

Between two narrow borders are formed successive irregular rectangles by the fantastically bent stripe *h*. These rectangles are respectively marked *g*, *f*, *i*, *m*, and *k*. The largest of these are the rectangles *f* and *k*. Within the rectangle *f* is the figure *G*, the most prominent part of which is a representation of a flower having lancet-shaped leaves projecting from a stem and surrounded by a series of star-like flowers, *e*. The stem of the flower *G* extends

into the field *i* and bears within the same star-like flowers. The smaller rectangle *m* contains a circular figure with a rosette-like center. The rectangle *k* contains a group, *F*, of plum-like fruits, suspended from a branch, *j*, adjoining a central floral group, as shown. Some of these fruits extend over and partly fill the space intervening between the figures *k* and *g*. The rectangle *g* contains a prominent rosette, as shown.

I claim—

1. The design for wall-paper, consisting of the stripe *h*, forming figures *g*, *f*, *i*, *m*, and *k*, substantially as shown.

2. The design for wall-paper, consisting of the stripe *h*, forming figures *g*, *f*, *i*, *m*, and *k*, and of the groups *F* and *G*, substantially as shown.

EDUARD LEISSNÈR.
